3 Claims. (Cl. 92—168)

This invention relates to a lift structure and more particularly to a bearing structure used in guiding the movement of an automotive lift piston relative to a lift cylinder, although not necessarily so limited.

An object of this invention is to provide an improved bearing structure for an automotive lift.

A conventional automotive lift employs a superstructure which is attached to the top of a piston or ram slideable vertically within a cylinder mounted in a pit. The slideable movement of the piston relative to the cylinder is normally guided by a pair of spaced bearing rings affixed to the cylinder. In operation, either compressed air or fluid under pressure forces the piston upwardly within the cylinder until stop members at the base of the piston engage the lower bearing rings or other cooperating stop elements within the cylinder.

There are two basic types of conventional lift bearing structures. One type employs a lower bearing ring welded or otherwise permanently attached to the cylinder. With conventional permanently attached lower bearings, it is impossible to remove the piston from the cylinder without either destroying the bearing structure or removing the cylinder from the pit within the floor or ground in which it is placed. The other type has a removable lower bearing which is in threaded engagement with the internal surface of the cylinder or is otherwise removably attached thereto. The latter type of bearing structure is usually preferred since the piston may more readily be removed from the cylinder for repair.

A more specific object of this invention is to provide an improved removable lower bearing for use in a lift structure.

A further object of this invention is the provision of an improved upper bearing structure having advantages which will be discussed below.

Other objects and advantages reside in the construction of parts, the combination thereof, the method of manufacture and the mode of operation, as will become more apparent from the following description.

Referring to the drawing:

FIGURE 1 is a cross-sectional view, with portions broken away, of a lift structure made in accordance with this invention.

FIGURE 2 is a perspective view, with portions cut away, of an upper bearing and a bearing supporting gland ring used in the lift of FIGURE 1.

FIGURE 3 is a perspective view, with portions cut away, of a lower bearing ring used in the lift of FIGURE 1.

FIGURE 4 is a perspective view of a spanner wrench used in removing the lower bearing ring shown in FIGURE 3.

Referring to FIGURE 1, a lift structure is shown therein including a cylinder member 10 enclosed at its lower end by a base plate 12. The cylinder may be supported by struts 14 upon a base fixture 16. Normally, the fixture 16 will be located at the bottom of a pit formed in the earth or a floor. A piston or ram 18, which is cylindrical in shape and concentric with the cylinder 10, is mounted for vertical movement within the cylinder 10. The piston or ram 18 is provided with a base plate 20 at its lower end. The top of the piston 18 comprises a ram bolt ring 22 welded thereto, the bolt ring 22 being provided with a plurality of threaded apertures (not

2

shown) adapted to receive bolts for securing a lift superstructure (not shown) thereto. The bases of the threaded apertures are sealed by a sealing ring 26. To complete the top of the piston, a seal plate 28 is clamped in sealing relation to the bolt ring 22 by a plurality of clamp plates 30 connected to the ring 22.

The lift shown in FIGURE 1 is of the type known as "semi-hydraulic." During installation, the piston 18 and the cylinder 10 are filled nearly full with hydraulic fluid through an aperture, which is normally closed by a fill plug 32, located in the plate 28. To completely fill the cylinder 10 around the piston, a bleeder valve 24 is placed in communication with the cylinder 10 through an aperture 34 therein. In operation, air under pressure is supplied to the top of the piston 18 through an air tube 40 projecting longitudinally therethrough which communicates with an air inlet port 42 located in the base fixture 16. The compressed air acts against the top of the piston 18, causing it to rise above the top of the fluid. As the piston rises, the fluid therein is forced through a port 44 located centrally of the base plate 20 into the cylinder 10. A metering structure 46, located in the port 44, controls the rate of fluid flow passing therethrough, in turn to control the speed of movement of the piston. As shown in FIGURE 1, the metering structure 46 may simply comprise an apertured plate.

The air tube 40 is supported by a generally conical support member 50 secured to the base plate 12 of the cylinder 10. To protect the air tube 40 during shipping, a conical shipping protector 52 is attached to the bottom surface of the seal plate 28. The member 52 also serves as a baffle to supply compressed air equally in all directions when the piston is initially raised.

Mounted within the upper portion of the cylinder 10 in sealing relation to the piston 18 are an upper bearing structure 60 and a packing assembly generally designated 62. The packing assembly includes a packing gland ring 66 secured, as by a plurality of bolts 68, to a cylinder bolt ring 70 welded to the top of the cylinder 10. The bolt ring 70 may be integral with a packing support ring 72 which projects downwardly into the interior of the cylinder 10 and is provided at its lower end with an inwardly projecting flange or lip portion 74. The packing itself may comprise a plurality of Chevron-shaped packing members 76 sandwiched between a snap ring 78 supported on the flange portion 74 and the gland ring 66. This type of packing assembly has been found quite satisfactory in preventing hydraulic fluid from seeping out around the piston wall. To maintain the surface of the piston 18 clean at all times so as to prevent oil adhered to the surface of the piston from being removed from the piston and to prevent dirt or grit from entering into the cylinder, a wiper ring 80 may be secured within an annular channel 80a (FIGURE 2) cut in the inner periphery of the gland ring 66 adjacent the surface of the piston 18.

The upper bearing structure 60 may conveniently comprise a strip of bearing material snap fit within a second annular channel cut in the inner periphery of the gland ring 66. With the upper bearing structure 60 located above the packing 76, the packing 76 has a long useful life. Were the bearing structure 60 located below the packing, a certain amount of side play of the piston relative to the cylinder 10 would result, thus creating uneven pressure on the packing members 76. However, with the bearing structure 60 located above the packing, there is little side pressure on the packing member 76. Also, it is well known that a maximum separation between the upper and lower bearings is desirable to achieve the greatest control over the piston movement. This is best obtained by locating the upper bearing adjacent the top of the cylinder above the packing. Since the bearing 60

is snap fit within a channel in the gland ring 66, the cost of the upper bearing is quite small compared to conventional bearings. Also, this structure may be more rapidly assembled than is the case with most prior bearing structures.

The lower bearing structure, designated 82, includes a mounting ring 84 permanently affixed to the internal wall of the cylinder 10 intermediate its ends. The lower portion of the inner surface of the mounting ring 84 is threaded to accommodate external threads 86 on a lower bearing ring, generally designated 88, and shown best in FIGURE 3. The lower bearing surface is formed on the internal faces of a plurality of circumferentially spaced bearing pads 90, which are substantially equally spaced about the internal circumference of the ring 88. The bearing pads 90 are generally rectangular throughout their length, having generally parallel opposed sides 92 and flat bases 94, which are coplanar with the bottom face of the ring 88. The upper portions of the bearing pads 90, however, are tapered or sloping, as designated at 96, terminating in a pointed top 98. In FIGURE 3, the tapered portions 96 are shown as being straight. However, the sides 92 may depend more or less arcuately outwardly from the tops 98 to the bases 94. The use of spaced bearing pads 90 has several advantages over conventional prior art bearing structures having continuous solid bearing faces. Of course, an important advantage of such a structure is that foreign matter in the hydraulic fluid will pass between pairs of bearing pads 90 rather than passing along the bearing surfaces thereof. The sloping sides of the upper portions of the pads 90 induce foreign matter to pass between the pads as the piston is being raised. Thus, the life of the bearing surface is prolonged. In addition, air pockets often become trapped beneath solid lower bearing structures hampering the normal operation of the lift. Because the bearing pads 90 are spaced, such air pockets obviously cannot form.

In use, the bearing ring 88 is located, as shown in FIGURE 1, in threaded engagement with the mounting ring 84. Normally, the piston or ram 18 cannot move upwardly beyond a limit provided by an enlarged flange 100 formed on the base of the ram 18, which stops against the lower surface of the ring 88. In the past, it has been common to connect lower bearing rings to upper bearing rings by means of a metal sleeve so that removal of the two bearings could be accomplished at the same time. However, it is not feasible to connect the upper and lower bearings where, as here, the upper bearing ring is located above the packing. In accordance with this invention, the lower bearing ring is locked in position by detent means but may be removed by use of a spanner wrench, as will be described below.

As shown best in FIGURE 3, a pair of diametrically opposed notches 102 and 104 are cut in the upper portion of the lower bearing ring 88. The lower ends of the notches 102 and 104 are defined by inwardly tapered surfaces designated 106. During assembly, when the ring 88 is threaded into engagement with the ring 84, a detent plunger member 108, which is spring biased by a spring 110 and located within a housing 112 mounted in aligned apertures in the mounting ring 84 and the cylinder 10, enters into one of the notches 102 and 104, preventing further rotation of the bearing ring 88. In practice, the bearing ring 88 will be threaded into engagement with the mounting ring 84 by means of a spanner wrench 114 (FIGURE 4). The spanner wrench 114 comprises a generally elongate sleeve, having a pair of lugs 116 depending from its lower surface and a pair of handle bars 118 affixed to the upper portion thereof. Only one lug 116 may be seen in FIGURE 4, since the other lug 116 is hidden by the side of the sleeve. The handle bars 118 are diametrically opposed one to the other and each is aligned with one of the lugs 116. When installing a bear-

ing ring 88, the spanner wrench is slipped over the piston 18 and the lugs 116 inserted within the notches 102 and 104. The bearing ring 88 is then rotated a predetermined number of revolutions. The person installing the bearing ring 88 will be aware that the plunger 108 has begun to enter one of the notches 102, 104 because of a slight click caused by the plunger 108 striking one of the lugs 116. The spanner wrench 114 is then withdrawn. The packing in the upper bearing ring assembly can then be affixed in position on the top of the cylinder. Removal of the lower bearing is accomplished in the same fashion. Note that each lug 116 has an inwardly tapered bottom face 116a, one of which serves to cam the plunger 108 outwardly into the housing 112 so that the bearing ring 88 may be removed from its engagement with the mounting ring 84. Proper lubrication of the plunger 108 and of the threaded portion 86 of the ring 88 is insured by means of lubricating channels 120, 122 cut in the outer surface of the 88.

Although the presently preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described our invention, we claim:

1. In a vehicle lift having a cylinder and a piston, a bearing structure including a mounting ring connected to said cylinder, a bearing ring having a bearing surface in contact with said piston, said bearing ring being in threaded engagement with said mounting ring, detent means supported by said cylinder including a detent member adapted to enter a notch in said bearing ring to lock said bearing ring in a predetermined position, said detent member being removable from said notch.

2. In a lift structure, the combination including: a cylinder, a piston movable within said cylinder, a packing structure including a packing gland ring located adjacent the top of said cylinder and supported thereby, an upper bearing structure adjacent the top of said cylinder in contact with said piston comprising a strip of bearing material located within a channel in said gland ring, a lower bearing structure intermediate the ends of said cylinder, said lower bearing structure including a mounting ring connected to said cylinder, a bearing ring having a bearing surface in contact with said piston, said bearing ring being in threaded engagement with said mounting ring, detent means supported by said cylinder including a detent member adapted to enter a notch in said bearing ring to lock said bearing ring in a predetermined position, said detent member being removable from said notch, said piston being provided with an enlarged annular flange at its lower end adapted to engage the bottom surface of said lower bearing ring.

3. A bearing ring for a vehicle lift having a cylinder and a piston, said ring having a plurality of circumferentially spaced bearing pads on the internal face thereof, each of said pads having a bearing surface adapted to contact said piston, and the upper portion of each of said bearing pads having sloping sides.
